LOCK FOR FLOOR SAFES

Filed Nov. 1, 1926

UNITED STATES PATENT OFFICE.

HARRY W. HAHN, OF LOS ANGELES, CALIFORNIA.

LOCK FOR FLOOR SAFES.

Application filed November 1, 1926. Serial No. 145,599.

- This invention relates to locks for floor safes, and a primary object is to provide a simple, economical and efficient type of device adapted to be conveniently located on a safe which is adapted to be imbedded in the floor of a shop, store, office or other kind of building, and so arranged that it is incapable of being tampered with for the purpose of gaining access to the interior.
- 10 A still further object is to provide a pair of locks one of which will lock the sliding bolts against operation by the other lock, thus necessitating the operation of both of said locks before access can be gained to the interior of the safe.
- Still other objects may appear as the description progresses.
- I have shown a preferred embodiment of my invention in the accompanying drawings, 20 subject to modification within the scope of the appended claims without departing from the spirit thereof, in which:
- Fig. 1 is a top plan view of a floor safe embodying my improvements.
- 25 Fig. 2 is a sectional elevation of the same, as seen on line 2—2 of Fig. 1.
- Fig. 3 is a sectional plan of the same on line 3—3 of Fig. 2.
- Fig. 4 is a fragmentary section of the same 30 on line 4—4 of Fig. 1.
- Fig. 5 is a perspective view of the lock housing; and
- Figs. 6 and 7 are perspective views of the locking bolts operably supported in the housing shown in Fig. 5.
- Briefly described, my invention is adaptable to a receptacle having a cylindrical body B, closed at the bottom by means of a disc D and provided with an annular top T, in 40 which is held a removable cover C. Said cover is provided on the lower side with a lock housing H which serves to enclose a pair of locking bolts b and b', adapted to be operated and controlled by means of a pair of 45 cylinder locks L and L'.

The safe as shown is adapted to be imbedded in a concrete or cement floor, as at F, and the bottom member D and top member T are of greater diameter than the body member B, so that said bottom and top members will project over the body and the cement

will fill the spaces between said top and bottom members, so as to render the safe incapable of removal from the floor. Also, the bottom member D is constructed preferably 55 in the form of a polygon, with a plurality of sides 1, 1, etc., eight of such sides being shown in the drawing, so as to prevent the turning of the receptacle in the floor by accident or design, and to cause the safe to be 60 stationarily held in position.

The body B is formed preferably of round steel tubing of substantial diameter, so as to provide a compartment I in the safe for the reception of money and articles of value. 65 The bottom D is formed of a plate of steel which is preferably attached to the lower end of the body B by arc welding in the fillets f, f, etc. The top T is formed preferably of a piece of carbon-steel plate of substantial 70 thickness, and is likewise attached to the upper end of the body B by welding at the fillets f', f', etc. The top T is provided with a central stepped opening, as at O, which has the largest opening on its upper side and the 75 smallest opening on its lower side, providing a plurality of annular shoulders 2, 2, etc., of different diameter, which are adapted to correspond in size to and to receive a plurality of correspondingly and reversely formed portions 3, 3, etc., formed on the cover C, the larger of the portions 3 being at the top and the smaller of said portions at the bottom of the member C.

As indicated at 4, a gasket of rubber or 80 other suitable substance may be provided between the lowermost shoulders of the members T and C, for the purpose of rendering the receptacle proof against the entrance of water from the floor above, though this is immaterial to my invention.

The cover C has an angularly formed narrow slot S therein, through which money may be deposited in a compartment I of the safe, without removing the cover C. The 90 locking housing H is attached to the lower side of the cover C by means of a pair or more cap screws 5, 5, which are threaded into blind holes 6, 6, in the cover C and extend through apertures 7, 7 in the housing H. Said housing is rectangular in form and has a bottom portion 8, with sides 9, 9 and end portions 10

and 11, the edges of the sides, 9, 9 and the ends 10 and 11 abutting the lower side of the cover C.

The ends 10 and 11 of said housing are provided with rectangular openings 12 and 13, respectively, for slidably receiving the locking bolts *b* and *b'*, and by means of which said bolts may be extended from the housing H to positions beneath the annular top member T, so as to firmly lock the member C in position on the member T for closing the compartment I of the safe against unauthorized access.

The locking bolts *b* and *b'* are of rectangular form and are of substantial cross sectional area, said bolts being transversely disposed across and slidable on the member C on opposite sides of the locks L and L', as shown in Fig. 3. The members *b* and *b'* have recesses 13 and 14 formed in the central portions thereof, which are adapted to receive the end portions *e* and *e'*, respectively of a locking member E, which is suitably fixed to the rotating member 15 of the lock L. The member *b* is also provided with a recess 16 at its rear end, which receives the end portion 17 of an auxiliary locking member E' suitably fixed to the rotating member 18 of the lock L.

The locks L and L' are pressed, keyed or otherwise stationarily and irremovably held in the cover C, and the members E and E' are fixed to the members 15 and 18, respectively, of said locks by means of pins 19 and 20, or otherwise. The purpose of the two locks is to provide a double and extra safeguard against the manipulation of the locking device by unauthorized parties, or by accidental means.

The lock L is preferably positioned in the center of the cover C, while the supplementary lock L' is aligned therewith transversely, so that when it is desired to gain access to the safe it is first necessary to operate the lock L' before the lock L can be operated for retracting the bolts *b* and *b'* to permit the removal of the cover C. By reference to Fig. 3, it will be observed that when the cover is locked in position, as shown in said figure, the bolts *b* and *b'* are extended from the opposite ends of the housing H, respectively, so as to underlie the annular member T.

The bolt operating member E attached to the lock L, when the lock is turned in a given direction will move the bolts *b* and *b'* in opposite directions for either locking or unlocking the safe, but when the elements of the lock are in the position shown in Fig. 3, it is first necessary to operate the lock L' in a clock-wise direction for retracting the portion 17 of member E', so as to permit the retraction of the bolt *b* by the subsequent operation of the lock L. When the cover is locked in position the lock L is operated in a reverse direction from that stated, for extending the

bolts *b* and *b'* from the opposite ends of the housing H, and the lock L' is subsequently operated in a counter-clock-wise direction for moving the portion 17 of member E' against the end of the recess 16 in the bolt *b*.

Thus, keys to the locks L and L' may be held by two different persons and access to the safe can only be gained by the cooperation of the persons possessing the keys, and an additional safeguard is provided against the unauthorized removal of the contents of the safe.

It will be observed that I have shown and described herein a satisfactory and efficient type of floor safe and locking means therefor, which can be permanently held in the floor of a store or shop and locked against unauthorized access, so that it will serve as a safe and convenient means for safeguarding sums of money and articles of value against unauthorized removal.

What I claim is:

1. A lock comprising a supporting member, a casing supported thereon, a pair of notched bolts spaced apart and extensible in opposite directions into positions for locking said supporting member against removal, a primary lock having a centrally pivoted lever with oppositely extended arms within said casing directly engaging the notches of said bolts, and adapted to extend and retract the same, and a secondary lock having means directly engaging one of said bolts and adapted to lock both of the bolts against retraction until both of the locks are operated.

2. A lock comprising a casing, a pair of parallel spaced slidable bolts extensible through opposite ends of said casing into locking position, said bolts having correspondingly formed recesses therein, a primary lock rotatably supported on said casing and provided within the casing with an actuating member, and having oppositely extended arms seated in the recesses of and overlying said bolts for extending and retracting the same, one of said bolts having a second recess therein, a secondary lock rotatably supported in said casing and having an actuating member having a single arm mounted thereon within the casing, and seated in said second recess of one of the bolts for preventing the retraction of both of said bolts until both of said locks have been operated.

3. In a floor safe having a closure, a locking device mounted on said closure comprising a casing attached to the inner side thereof, a pair of parallel slidable bolts of rectangular cross section in said casing and extensible through opposite sides thereof respectively, one of the sides of each of said bolts being movable over the inner side of said closure, the opposite sides of said bolts being provided with recesses, and one of said bolts being provided with a second recess, a primary lock rotatably mounted in said closure

and having an actuating member attached thereto within said casing and provided with diametrically opposite portions overlying said bolts and seated in said first mentioned recesses thereof for moving the bolts in opposite directions when the lock is operated, and a secondary lock mounted on said closure and

having a member attached thereto within the casing overlying one of said bolts and seated in the said second recess for preventing the 10 operation of both of said bolts until and unless both of said locks are operated.

HARRY W. HAHN
